RADIATOR

Fred M. Young, Racine Wis., assignor to Young
Radiator Company, Racine, Wis.

Application September 7, 1935, Serial No. 39,611

3 Claims. (Cl. 257—125)

This invention relates to improvements in heat transfer devices commonly called radiators and more particularly the type used for cooling large internal combustion engines, wherein the radiator is mounted on the engine supporting frame, or for use on rail cars, busses, trucks and the like. In either event the radiator is subjected to considerable vibration.

The usual vibration in radiators of this type is serious, in that the tubes are made of thin copper and therefore are fragile and sensitive to vibration which sooner or later results in leaky joints where the tube ends are attached to the header plates.

15 In large radiators there is considerable weight in the core and the core is of considerable length. The center portion of the core oscillates sidewise. This oscillation is frequently quite noticeable and serious. The tubes do not greatly resist this side motion because they are usually flattened and positioned with the long section in a transverse direction to the direction of vibration.

20 The object of my invention is to provide simple and inexpensive means whereby the center of the core is held against a sidewise bending or oscillating movement. I accomplish these objects by means of a novel transverse anchor whereby the core about midway the headers, is secured to the side housing posts.

25 The preferred embodiment of my invention is illustrated in the accompanying drawing in which:

30 Figure 1 is a rear elevation of a radiator equipped with one form of my invention, a portion of the housing being cut away to clearly illustrate the manner of removably and adjustably securing the anchoring means to the housing.

35 Figure 2 is a fractional section taken on line 2—2 of Figure 1.

40 Figure 3 is a fractional section taken on line 3—3 of Figure 1.

Figure 4 is a fractional view of a modification.

45 Figure 5 is a fractional section of a modification, very similar to the device shown in Figure 1, except in the manner of attaching the anchoring members.

50 As thus illustrated numeral 15 designates the upper header plate of the radiator core and 16 designates the lower header plate. A plurality of vertical tubes 17 are suitably positioned in parallel relation and the ends bonded or otherwise made fast into corresponding openings in the plates 15 and 16.

55 The upper header cap 18 is made fast to upper

header plate 15 by means of a gasket and suitable bolts or otherwise attached. In Figure 1, I illustrate my preferred design wherein the header or tube plate 15 is very thin and is held to the flange of header cap 18 by means of the ends of housing members 19 and suitable bolts and center plates, and the lower header cap 20 is similarly made fast to the lower tube plate 16. In the design shown, housing members 19 form a protection for the core sides and have sufficient rigidity to answer as an anchor for the upper header and for the core center as will hereinafter appear.

5 The header cap 18 is supplied with the usual filler cap nipple 26 and a coolant inlet opening 27. The lower header cap 20 is preferably provided 10 with coolant outlet openings 28—28. Thus when the proper connections are made, the coolant may pass into the header cap 18, down through tubes 17, into header cap 20 and out through openings 28.

15 In order to increase the radiating capacity of the device, closely spaced fins 29 are provided. These fins are provided with flanged openings (not shown) through which the tubes extend and are bonded thereto in the usual manner.

20 Thus it will be seen that I have shown a conventional radiator the tubes of which are preferably flattened in cross section.

25 If the core is supported from the lower header only, the top header, unless suitably held, may oscillate sidewise to a considerable extent and cause loose joints or fractured tubes. When the upper header is held sufficiently rigid by the housing to prevent side movement, as illustrated in Figure 1, the core itself at its center, may be caused to vibrate sidewise and cause trouble at either end of the tubes. I provide novel means therefore, to prevent all side movement or vibration in the following manner:

30 Short U shaped rods 30 are positioned between certain fins, preferably two or more in front and two or more in the rear of the tubes 17, the ends passing through openings in end plates 31 which are laid on the ends of the fins. The ends of members 30 are flanged over in counter-sunk openings and made fast by bonding or welding, after 35 which these members are also bonded to adjacent fins for their length.

40 Thus this assembly will be firmly held to adjacent fins. The end plates 31 are preferably 45 provided with bolts 32 which protrude through openings in the side walls of the housing, as indicated in Figure 1. After this assembly is completed acorn nuts 33—33 are placed on the bolts 32 and tightened. Thus the core is anchored and 50 55

held from vibrating by the relatively rigid and strong housing. Rods 30 may be positioned on one side only of the cores and any number or combination used and otherwise anchored to 5 housing members 19.

In Figure 4 I illustrate a modification wherein preferably U shaped fillers 40 are positioned on opposite sides of the core and between the ends of certain fins as illustrated. U shaped plates 10 41 are provided, the ends fitting snugly between certain fins and the inner surfaces lying on the ends of the fins and fillers 40. This entire assembly is then bonded together, providing substantial surfaces on opposite sides of the core preferably midway the headers.

I provide preferably adjusting bolts 42, having lock nuts 43, which register with the center of plates 41, whereby after the assembling of the radiator has been completed, bolts 42 may be 20 made to press lightly against the plates 41 and thereby anchor the core in its normal position.

In Figure 5 I illustrate a modification of the device shown in Figures 1, 2, and 3 wherein the U shaped bars 45 are placed over the edges of the 25 fins instead of between the fins. In this design openings 46 are provided at closely spaced intervals in order to facilitate the bonding operation.

In radiators as shown the housing is, as already stated, rigid enough to hold the upper header from 30 vibrating or oscillating sidewise. The principal desideratum is therefore, to provide a housing sufficiently rigid to prevent side motion of the upper header relative to the lower header, and then bind the center portion of the core to the 35 housing structure in a manner which will effectively hold the center portion of the core from side oscillation.

Thus it will be seen that I have provided novel means for anchoring the center of the core to 40 thereby prevent harmful distortion and vibrations.

Having thus shown and described my invention what I claim is:

1. A radiator of the class described, comprising upper and lower headers, side housing mem- 45

bers rigidly connecting the ends of said headers together forming a frame, a number of tubes having operating connections between said headers, a multiplicity of closely spaced fins through which said tubes extend forming a core, plates positioned on opposite sides of said core, midway said headers, having flanged edges which extend between certain fins and rest on the end tubes, and adjustable means on said housing members contacting said plates to thereby anchor said core 10 therebetween. 5

2. A core anchoring device of the class described, in combination with upper and lower headers, side housing members rigidly connecting the adjacent ends of said headers forming a 15 frame, a number of tubes having operating connections between said headers, a multiplicity of closely spaced fins through which said tubes extend forming a core, said anchoring device comprising reinforcing members attached to opposite 20 sides of said core midway said headers, and adjusting means on said housing members adapted to be moved in pressure contact with said reinforcing members whereby said core may be anchored 25 in its normal position therebetween after the assembly of said frame and core is completed.

3. A core anchoring device of the class described, in combination with upper and lower headers, side housing members rigidly connecting 30 the adjacent ends of said headers forming a frame, a number of tubes having operating connections between said headers, a multiplicity of closely spaced fins through which said tubes extend forming a core, said anchoring device comprising reinforcing members attached to opposite sides of said core midway said headers and adjustable anchoring means on said housing members registering with said reinforcing members whereby after said core and frame have been assembled, said adjustable means may be moved into contact with said reinforcing members whereby said core may be 40 adjustably contacted and held in its normal position.
